United States Patent Office.

EDWARD A. GALBRAITH, OF BOSTON, MASSACHUSETTS, ASSIGNOR TO HIMSELF AND PAUL P. TODD, OF SAME PLACE.

Letters Patent No. 79,221, dated June 23, 1868.

IMPROVEMENT IN LAMP-BURNERS.

The Schedule referred to in these Letters Patent and making part of the same.

TO ALL TO WHOM THESE PRESENTS SHALL COME:

Be it known that I, EDWARD A. GALBRAITH, of Boston, in the county of Suffolk, and State of Massachusetts, have invented certain new and useful Improvements in Lamp-Burners, for burning kerosene or other volatile illuminating-oils; and do hereby declare the following to be a full, clear, and exact description thereof, due reference being had to the accompanying drawings, making part of this specification, and in which—

Figures 1 and 2 are vertical sections of a lamp-burner, constructed in accordance with the principles of my invention.

Figure 3 is a top view of it, with its conical deflector removed.

I have had several objects in view in producing the burner in question, one of such objects being to extract and utilize the vapors arising from the fluid within the lamp, and by this means not only increase the illuminating power of volume of the flame, but do away with the great objection to kerosene-burners, as at present constructed, of their possibility as well as liability to explosion by the ignition of these vapors within the lamp.

Another object sought in making this invention is to introduce oxygen to the interior of the flame at the top of the wick-tube, thus creating perfect combustion of the oil, and producing a clear and brilliant flame, but also preventing to a great extent the "charring" or burning of the end of the wick.

Still another object of my present invention is to insulate the conical deflector from the body of the burner, for the purpose of preventing radiation of heat from such deflector to the lamp and its contents.

The invention consists, first, in applying, within the wick-tube of a lamp-burner, of a second and auxiliary tube, or two plates, so arranged that two wicks may be employed within the primary wick-tube, and upon opposite sides of the auxiliary tube, the purpose of such auxiliary tube being to allow of the ascent of vapors, from the body of the lamp, upward between the two wicks or two portions of one wick.

The invention further consists in combining with such auxiliary tube or plates, and the primary, two branch-pipes or air-ducts, leading from opposite sides of the upper end of the two tubes to the exterior of the burner, the oxygen admitted through these ducts serving the purpose not only of aiding in a perfect combustion of the fluid contained in the lamp, but also, by mixing with the vapors ascending through the auxiliary tube, convert such vapors into an illuminating-gas, the oxygen further having the effect of preventing charring of the upper end of the wick, as before mentioned.

The invention further consists in the interposition of an annulus or strip of India rubber between the conical deflector and the body of the burner, by which heating of such burner and the lamp and its contents by radiation from the deflector is prevented.

In the drawings, *a* denotes a lamp-burner of any well-known or proper construction, *b* being its conical deflector, and *c* its primary wick-tube, such tube being provided with the usual wick-elevating wheels and shaft.

My invention consists as follows: *d* denotes an arched pipe or conduit, extending laterally through the top of the wick-tube, and with its extremities extending through opposite sides of the burner. A vertical opening, *e*, corresponding in length, or thereabouts, with the width of the interior of the wick-tube, being made centrally in the top of such pipe, *d*, for allowing of the passage of oxygen through the pipe *d* to the flame.

Depending from the bottom of the pipe *d*, and centrally of the wick-tube, is a short auxiliary tube or partition, *f*, which divides the upper portion of the wick-tube into two parts, and serves the purpose of dividing the two wicks contained in the tube *c*, and leaving a space between them for the admission of air issuing from the aperture *e* of the pipe *d*.

Furthermore, a second pipe or conduit, *g*, is affixed to the lower part of the burner, and alongside of the wick-tube, and opening into the body of the lamp, such tube extending some distance up the side of the wick-tube, and having two diverging branches, *h h*, communicating with the arched pipe *d*, upon opposite sides of such wick-tube, as represented in fig. 1 of the drawings.

In operating with the above-described burner, two wicks are to be placed within the tube *c*, and extended upward and upon opposite sides of the air-conduit *d*.

Upon inflaming such wicks, a draught is created through the said conduit *d*, and a current of oxygen caused to pass through it, and between the two wicks, and into the centre of the flame, or between the flames, thus introducing the oxygen at the most desirable point, and producing a flame of great brilliancy.

The admission of oxygen at this point also has the effect of preventing charring or burning of the wick, to a great extent, and require trimming of it to be done only at comparatively long intervals of time.

The vapor contained or forming in the body of the lamp above its supply of oil, will be drawn upward through the conduit *g*, and into the arched pipe or air-conduit *d*, and combining with the current of oxygen passing through it, will be converted into gas, and aid in increasing the volume of the flame, at the same time removing possibility of explosion of the lamp.

For the purpose of preventing heating of the lamp and its contents, by means of radiation of heat from the conical deflector *b*, I interpose between such deflector and the body of the burner an annulus or strip, *i*, of India rubber, or other non-conducting material or compound.

I would remark that in place of two wicks, one wick may be employed, doubled at its middle, and with its two ends inserted within the wick-tube.

I claim as my invention, and desire to secure by Letters Patent of the United States of America—

1. The combination, with the conduit for supplying air to the flame, of a vapor-conducting pipe, leading from the fluid-reservoir of the lamp, and communicating with the said air-conduit, substantially as and for the purposes herein shown and set forth.

2. A lamp-burner, in which the divided wick-tube, with its double wick, the air-supplying pipe or conduit, and the vapor-conduit are combined and arranged for joint operation, in the manner herein shown and described.

EDWARD A. GALBRAITH.
